UNITED STATES PATENT OFFICE.

JOHN L. HOOVER, OF SHELBYVILLE, ILLINOIS.

GOLF-TEE MOLD.

Application filed October 2, 1922. Serial No. 592,098.

To all whom it may concern:

Be it known that I, JOHN LOUIS HOOVER, a citizen of the United States, residing in Shelbyville, in the county of Shelby and 5 State of Illinois, have invented certain new and useful Improvements in Golf-Tee Molds, of which the following is a specification.

This invention has reference to golf tee 10 molds and its object is to provide a mold which may be very readily manipulated to form and place sand tees for holding the ball while being shot.

In accordance with the invention there is 15 provided a mold structure capable of producing a concaved cone of sand or earth on which to sustain the ball while being driven and for this purpose the mold comprises a metal receptacle capable of holding a small 20 quantity of sand or dirt to provide a support for the ball which latter is then placed upon the tee to be supported at appropriate distance above the surface of the ground.

In accordance with the invention the 25 mold is provided with a handle structure by means of which it may be lifted from place to place and located in the desired locality.

The invention will be best understood 30 from a consideration of the following detailed description taken in conjunction with the accompanying drawing forming a part of this specification, with the understanding that the invention is not confined to any strict conformity with the showing of the 35 drawing but may be changed and modified so long as such changes and modifications mark no material departure from the salient features of the invention as expressed in the appended claim.

40 In the drawings:—

Fig. 1 is a perspective view showing the mold and the tee in spaced relation with the tee resting on the ground.

Fig. 2 is a vertical central section through 45 the mold with the tee omitted.

Fig. 3 is a plan view of the mold.

Fig. 4 is a view showing the tee in operative position with a ball resting thereon.

Referring to the drawing there is shown 50 in Figure 1 a frusto-conical shaped mold 1 which may be conveniently made of metal, with a hollow interior 2 of frusto-conical shape of steeper contour than the exterior of the mold.

55 The exterior walls of the mold are more nearly vertical than the interior walls and

the mold is provided with a head or crown 3 of greater thickness than the side walls.

Extending through the crown of the mold 2 is a stem 4 having at its lower inner end 60 a knob or top 6. The head 5 has a convex lower face 7, and the head 6 is rounded on its upper face. Between the head 6 and the top of the mold the stem 4 is surrounded by a spring 8 of sufficient strength to hold the 65 stem 4 in the elevated position but at the same time offering no material resistance to the compression of the spring 8 when sufficient pressure is exerted on the head 6.

Secured to the top or crown portion of 70 the mold is a handle structure 9 which may be made of a single piece of wire sufficiently widened at the end remote from the mold to provide a convenient hand hold and the ends of the wire at the mold are spread 75 apart as indicated at 10 and embedded in the material of the mold so as to anchor therein whereby the hand hold is fixed in the mold so that the latter may be conveniently handled and placed at any point de- 80 sired.

When the tee mold is in use, the mold is filled with sand or dirt, which material is compacted thereinto against the head 5, the strength of the spring 8 being sufficient to 85 hold the stem 4 with sufficient firmness against the crown 3 of the mold.

The tee material is compacted into the mold and may be of a nature to hold its shape therein and then when it is desired to 90 discharge the tee from the mold, the stem 4 is manipulated by pressure applied to the head 6, thus discharging the tee, and at the same time, permitting the raising of the mold, leaving the tee, shown at 11, deposited 95 on the ground.

There is formed in the upper smaller end of the tee a concavity 12 into which the golf ball, indicated at 13, will rest, the mold being in the meantime discarded.

100 The mold, because of the presence of the handle 9 may be very readily manipulated and the contents, the tee, may be discharged with the greatest facility and without liability of injury to the tee. Moreover the 105 molds because of their rigidly connected handles, do not cause any disturbance of the material from which the tees are made and so no harm may come to the tees either in their molding or in the placing thereof.

110 What is claimed is:—

In a golf tee mold, a frusto-conical mold

having interior and exterior walls, an upwardly and outwardly inclined handle member consisting of a heavy, substantially U-shaped wire, widened at the looped end 5 and constricted near its free ends, the said free ends diverging from the constricted portion and bending downwardly and pass-

ing into the top of said mold at two points, and a spring supported ejecting means passing through the top of the form medially 10 of the diverging handle ends.

In testimony whereof, I affix my signature hereto.

JOHN L. HOOVER.
